UNITED STATES PATENT OFFICE.

FRED J. NUTTING, OF DAYTON, OHIO, ASSIGNOR, BY MESNE ASSIGNMENTS,
TO THE NATIONAL CASH REGISTER COMPANY, OF JERSEY CITY, NEW
JERSEY.

AUTOGRAPHIC REGISTER.

SPECIFICATION forming part of Letters Patent No. 664,359, dated December 18, 1900.

Application filed September 22, 1897. Serial No. 652,560. (No model.)

To all whom it may concern:

Be it known that I, FRED J. NUTTING, a citizen of the United States, residing at Dayton, in the county of Montgomery and State of Ohio, have invented certain new and useful Improvements in Autographic Registers; and I do hereby declare the following to be a full, clear, and exact description of the invention.

My invention relates to that class of autographic registers in which the record-strip after it has passed over the writing-tablet is led into the machine and folded back and forth in bellows form in the storage-compartment instead of being wound upon a receiving-roll, as is usual in this class of machines.

My invention consists particularly in the novel means employed to accomplish this end.

In the accompanying drawings, Figure 1 is a vertical longitudinal section through the center of the machine on the line 1 1 of Fig. 2. Fig. 2 is a top plan view of the machine with the top casing and the platen removed. Fig. 3 is a vertical longitudinal section on the line 3 3 of Fig. 2, with the walls of the storage-compartment, the platen, and the clamping-hooks, which are shown in Fig. 1, omitted. Fig. 4 is a view of the superimposed cams employed to alternately open and close the folding-blades. Fig. 5 is a perspective view of one of the slides which carry the folding-rollers. Fig. 6 is a detail sectional view of the handle of the platen, showing the stem, which is elliptical-shaped in cross-section. Fig. 7 is a detail view showing a portion of one of the side walls of the filing-compartments with a bracket secured thereto. Fig. 8 is a detail perspective view of the holder for securing the end of the record-strip to the platen.

The same letters of reference indicate identical parts in all the figures of the drawings.

The working parts of the machine are enclosed within the usual casing A, having a usual top B, which is transversely slotted at b, b', and b''. The portion of the lid lying between the slots b' and b'' forms the writing-tablet C, over which the paper sheets are led from the record-roll C' and the check-rolls C² and C³. Carbon-sheets are in practice interposed between the record-strip c' and the check-strips c² and c³ in the usual manner,

and after the proper record has been made upon the top sheet the checks are torn off at the slot b², while the record-strip is led into the machine through the slot b' and down to 55 the folding mechanism, where it is manipulated in a manner I shall presently describe. The crank D is fixed upon a short shaft which extends through the side of the case A, and upon its inner end is secured the driving-gear E, which is also secured to and turns the lower feed-roller e, which co-operates with the upper feed-roller e' to feed the check-strips when the crank is turned. The record-strip c', it will be noted, is not moved by the feed-rollers, but by means of the folding mechanism, as I shall presently describe. Meshing with the driving-gear E is an intermediate gear F, which in turn meshes with the main gear F'. A short shaft G is secured at one 70 end to the main gear and is driven thereby. Upon its other end is secured the bevel-gear g, which meshes with and drives the horizontal bevel-gear g'. This is secured upon the short vertical shaft G', upon the lower end of 75 which are secured two superimposed partly-circular cams H H', which are shown in detail in Fig. 4 of the drawings and which are for the purpose of opening and closing the folding-blades, as will presently be described. 80

The record-strip c', extending over the writing-tablet C, re-enters the machine through the slot b' and is led thence between a pair of folding-rollers I I', which at their ends are journaled in a pair of reciprocating slides J 85 J', which slide inside the machine in parallel grooves or slideways J², which are formed in the opposite sides of the case A. Upon its under side each slide carries a rack J³, which meshes with the segment-rack K, which is 90 pivoted at K' to the side of the case of the register. Driven from the main gear F' is a crank-arm F², and a link F³ is pivoted at one end to the crank-arm and at the other end to the body portion K² of the segment-rack. 95

It will be readily seen from the mechanism thus far described that when the crank D is turned motion will be transmitted through the gears F and F' and the link F³ to vibrate the segment-rack K, which in turn will reciprocate the slides J and the folding-rollers I I', carried thereby. 100

The storage-compartment is rectangular in cross-sections, being formed by transverse walls L L between the inner frames A'. When the crank is turned, the folding-rollers I I' 5 reciprocate lengthwise of the machine, the travel being from one of the transverse walls L to the other. Fitting within the storage-compartment and movable vertically therein is the horizontal platen M. Near the corners of the storage-compartment (see Fig. 2) are four vertical rock-shafts N, the lower end of each passing through the bottom of the case A (see Fig. 3) and each having a collar n secured upon its lower end. Coiled on each 15 rock-shaft is a helical spring n', which at its lower end is fastened to the case or other fixed part of the machine. At its upper end it is fastened to the rock-shaft, so that if any rock-shaft be rocked or turned from normal position the spring will return it to normal position as soon as it is released. Near their upper ends the rock-shafts each has a bearing in one of the four brackets N', which are rigidly secured, preferably, to the walls of the 20 storage-compartment, and upon its upper surface each of said brackets N' has a radially-extending rib n'', for a purpose to be presently described.

Secured rigidly to the rock-shafts at the upper ends thereof are two pairs of folding-blades N² N³, respectively. Rigidly secured to each rock-shaft near the lower end thereof is one of four arms N⁴, for a purpose to be presently described.

30 Mounted to slide upon the floor or bottom of the case of the machine are a pair of reciprocating frames O O', and each frame consists of a cross-bar, at the ends of which are short parallel arms o o, respectively, which extend lengthwise of the machine, and these frames are arranged to alternately open and close the pairs of folding-blades, as will be presently described. Secured upon the vertical shaft G', near the lower end thereof and turning therewith, are the superimposed partly-circular cams H H'. A hook-shaped bar P is pivoted at its left-hand end to the reciprocating frame O', and its right-hand end bears upon the periphery of the lower cam H'. A straight bar P' is pivoted at its left-hand end to the other reciprocating frame O and at its right-hand end bears against the periphery of the upper cam H. Helical springs p, connected at their ends to the reciprocating 40 frames, exert a pressure tending to draw the frames together, thereby holding the bars P P' closely against the periphery of their respective cams, and the cams are so positioned with respect to each other that when the crank D is turned the reciprocating frames will be actuated to alternately open and close the folding-blades. With the operating parts as shown in Fig. 2, for example, after the crank D has been turned in the direction of the arrow a certain distance the reciprocating frame O will be driven to the left, and the ends of the short parallel arms o will strike the

arms N⁴, one of which is secured to each rock-shaft N near the lower end thereof, and as the reciprocating frame O continues to advance toward the left the rock-shafts N, upon which the folding-blades N² are secured, will be rocked, and as the folding-blades, as previously described, are rigidly secured upon the upper ends of these rock-shafts the folding-blades will be turned inward to the closed position in which the blades N² are shown in Fig. 2 of the drawings.

By reference to Fig. 3 it will be seen that each folding-blade is secured to a hub n³, and projecting from the lower surface of each hub is a radially-extending rib n⁴. As the blades open outward their respective ribs n⁴ strike the ribs n² of the brackets N', and upon further movement of the blades the ribs ride over each other and then drop back, thus causing a temporary elevation of the folding-blades, for a purpose to be presently described. It will be observed that when the ribs ride over each other the rock-shafts are raised against the force of the spring n', the collar n being secured upon the lower end of the rock-shaft and far enough below the bottom of the case A to permit the necessary elevation of the rock-shafts and of the folding-blades carried thereby. The several ribs n² n⁴ are so positioned that the folding-blades are elevated just as they start from open toward closed position.

The handle Q is rigidly secured upon the lower end of the vertical shaft q, which at its upper end turns in a suitable bearing formed in the platen M. (See Fig. 1.) In cross-section the vertical shaft q is elliptical (see Fig. 6) and, for example, if it is desired to lower the platen and fasten it at a low position for convenience in removing the paper it is only necessary to give the handle Q a quarter-turn, whereupon the shaft q, being elliptical in cross-section, when turned will drive the plungers Q' against the transverse walls L of the storage-compartment. The said plungers slide freely in supports Q², which are secured to the under side of the platen, and when the handle is returned to the position shown in Fig. 1 suitable springs q' return the plungers to normal position, thereby releasing the platen and permitting the helical supporting-springs Q³ to force it upward against the folded paper or, if there be no folded paper in the storage-compartment, against the swinging ends of the clamping-hooks R R', of which there are four, one near each corner of the storage-compartment. These hooks operate in pairs, the hooks R being secured upon the ends of the transverse shaft R², which is suitably journaled in brackets r, secured to the transverse walls L, (see Fig. 1,) and the hooks R' upon the ends of the shaft R³, parallel to the shaft R² and on the opposite side of the storage-compartment. The ends of the hooks R R', which project into the storage-compartment, are beveled at r' and force the clamping-

hooks backward. The springs r^2 , coiled upon the shafts $R^2 R^3$, respectively exert normal pressure tending to swing the clamping-hooks so that their swinging ends will project into the storage-compartment and exert normally a spring-pressure upon the folded paper therein, as will be more fully described; but it is desirable that as the folding-blades approach closed position the clamping-hooks be retracted, and for this purpose the transverse rods $S S'$ are passed through and secured in the ends of the clamping-hooks $R R'$, respectively, and on one side the rods extend transversely, so that one end of each moves under the slide J' . Rigidly secured to the slide J' (see Fig. 5) are two downwardly-extending toes $j j'$, and as the slide J' reaches the extremes of its movement the toes strike the rods $S S'$ alternately to retract the clamping-hooks and permit the folding-blades to close.

In the practical operation of my invention the lid B is removed and the rolls C^1, C^2 , and C^3 are dropped into the machine, being supported by the horizontal spindles $C^4 C^5 C^6$, respectively, which are journaled in suitable bearings C^7 , secured to the inner frames A' . From the rolls the paper strips (see Fig. 1) are led through the slot b over the writing-tablet C , and the two top or check strips pass thence between the feed-rollers and out the slot b^2 . The third or record strip c' is led into the machine through the slot b' , thence between the folding-rollers $I I'$, and the end of the strip is secured to the platen M by inserting it under the holder T , (see Fig. 8,) which extends transversely of the platen and is pivoted at its ends to the sides thereof. When the crank is turned, the two top sheets are fed out in the usual manner, the movement of the handle is transmitted through the gears and the link F^8 to the segment-rack K , which in turn reciprocates the slide J , and by means of the connecting-shafts I^2 the slide J' is caused to reciprocate in unison with the slide J . As the end of the paper is fastened to the platen M , the reciprocation of the rollers causes the record-strip to be drawn from the roll C' . During the movement of the rollers toward the clamping-hooks the latter are retracted, and the folding-blades are first opened, and then they close in behind the folding-rollers, so that by the time the rollers are at an extreme of their travel the blades at that end of the storage-compartment are closed to form the loop and to retain it while the rollers make their return movement. When the rock-shafts are rocked, the ribs $N^2 N^4$ ride over each other, raising the folding-blades, so that they close above the part of the strip that is being drawn across the storage-compartment, and as the folding-rollers reach the extreme of their movement the folding-blades pass under the clamping-hooks, which are at that end. As the folding-blades reach closing position they force the paper loop under the clamping-hooks, and the folding-blades then remain in closed position

until the rollers travel to the other end of the storage-compartment and start on the return movement. As the folding-blades open the clamping-hooks grip the paper fold and press it down upon the folds which have been previously made. The coöperative action of the folding-rollers, the clamping-hooks, and the folding-blades are of course exactly the same at each end of the folding-compartments. When it is desired to remove the folded record-strip, the platen M is lowered by means of the handle, which is then given a quarter-turn to secure it in position. The record-strip may then be broken, preferably at a point between the folding-rollers and the slot b' , and thereupon the record-strip can be readily removed.

Having thus described my invention, I claim as new and desire to secure by Letters Patent—

1. In an autographic register, the combination with a record-strip-holding device, of pivoted folding-blades, and means for causing a periodical movement of said blades in a direction at right angles to the plane of the normal pivotal movement of the same.

2. In an autographic register, the combination with a record-strip-holding device, of slides, folding-rollers mounted on said slides, a rack on one of said slides, a pivoted segmental rack engaging the said first-mentioned rack, an operating-wheel and a link connecting said wheel and segmental rack.

3. In an autographic register, the combination with a record-strip-holding device, of folding-blades, sliding frames for operating said blades, an operating-shaft, a cam on said shaft and devices mounted on the frames so as to be engaged by said cam to reciprocate said frames.

4. In an autographic register the combination with a record-strip-holding device, of folding-blades for folding a record-strip, sliding frames arranged to engage and move said blades, springs connecting said frames, an operating means and independent devices for separately connecting said frames, to the operating means.

5. In an autographic register the combination with a record-strip-holding device, of folding-blades for folding a record-strip, sliding frames arranged to engage and move said blades, an operating-cam, a hook-arm pivotally connected to one of said frames and engaging the cam and flexible means connecting said frames.

6. In an autographic register the combination with a record-strip-holding device and a compartment into which a record-strip is to be folded, of a folding device, a movable platen in said compartment, movable plungers mounted on said platen, and means for operating the plungers to drive them against the sides of the compartment and thus lock the platen in any desired position therein.

7. In an autographic register the combination with a record-strip-holding device and a

- compartment into which a record-strip is to be folded, of a folding device, a movable platen in said compartment and devices for adjusting and securing said platen at any desired point in the compartment.
8. In an autographic register the combination with a record-strip-holding device and a compartment into which a record-strip is to be folded, of a folding device, a movable platen in said compartment, springs for normally forcing said platen upward and devices for locking the platen at any desired position in the compartment irrespective of the action of its springs.
9. In an autographic register the combination with a writing-tablet, of slides, folding-rollers journaled in said slides, a rack on one of said slides, a segmental rack engaging said first-mentioned rack folding-blades and a driving mechanism for moving the segmental rack and the folding-blades.
10. In an autographic register, the combination with a record-strip-holding device, of folding-rollers, folding-blades and means for causing a periodical movement of said blades in a direction at right angles to the plane of the normal movement of the same.
11. In an autographic register, the combination with a receptacle, of a record-strip-holding device, folding-blades for folding a record-strip in said receptacle, and means for causing a periodical movement of said blades in a direction at right angles to the plane of the normal movement of the same.
12. In an autographic register the combination with the means for drawing the record-strip to the storage-compartment, of means for folding said record-strip within the storage-compartment comprising the folding-blades arranged to be temporarily elevated at a certain point or points in their movement.
13. In an autographic register the combination with the storage-compartment, of the pairs of folding-blades disposed at opposite ends thereof, of the folding-rollers arranged to reciprocate from end to end of the storage-compartment and to reach the ends thereof substantially simultaneously with the closing of the pair of folding-blades which are located at that end.
14. In an autographic register the combination with the driving means, of the folding-rollers for drawing the record-strip to the storage-compartment, the clamping-hooks for holding the folded record-strip within the storage-compartment, and the reciprocating frames actuated by the driving means to open and close the folding-blades at predetermined points.
15. In an autographic register arranged to fold the record-strip the combination with the driving mechanism, of the folding-rollers reciprocated thereby, the swinging folding-blades, and the frames actuated by the driving mechanism and arranged to alternately open and close the folding-blades.
16. In an autographic register, the combination with a suitable frame, of a record-strip-holding device, folding-blades for folding a record-strip, projections on said blades, and stationary projections on the frame arranged to be engaged by the first-mentioned projections, whereby the blades are given a periodical movement in a direction at right angles to the plane of the normal movement of the same.

In testimony whereof I affix my signature in presence of two witnesses.
